UNITED STATES PATENT OFFICE.

HENRY C. SEIPP, OF PITTSBURGH, PENNSYLVANIA.

TILE FOR PAVEMENTS, SIDEWALKS, AND OTHER LIKE CONSTRUCTIONS.

1,146,961.

Specification of Letters Patent.

Patented July 20, 1915.

Application filed July 31, 1914. Serial No. 854,270.

To all whom it may concern:

Be it known that I, HENRY C. SEIPP, a resident of Pittsburgh, in the county of Allegheny and State of Pennsylvania, have invented a new and useful Improvement in Tiles for Pavements, Sidewalks, and other like Constructions; and I do hereby declare the following to be a full, clear, and exact description thereof.

10 The present invention relates to lights, lenses, or tiles for pavements, sidewalks, vaults, floor lights and other like constructions.

Heretofore, in the formation of lights in pavements, sidewalks, vaults, floor lights and such constructions, glass tile was generally used, which tile was made of a single piece of glass and pressed while hot in iron molds into a great variety of shapes. In 15 such tile, the designers strove to produce a transparent tile which would be unbreakable by the mere action of natural elements, such as expansion and contraction of the material in which the tile is embedded, as 20 well by the expansion and contraction of the tile itself, as by the action of heat and cold, such for instance, as the sun's rays on the upper surface upon the sidewalk containing such tile while the under side is 25 acted upon by the cooler atmosphere in the space under the side walk or within the vault, which condition is reversed in the winter or colder season, and the influence of 30 which has been very destructive to all glass tile heretofore used for this purpose. Designers have striven to devise a tile in which 35 the strain contained therein would be so evenly distributed as to produce a condition as nearly equal to elimination of strain as 40 possible, but this condition could not be obtained in a tile composed of a single piece of glass, as generally used for this purpose.

The object of the present invention is to 45 overcome these objections and to form a light for pavements, sidewalks, vaults, etc., which will be cheap, simple, and efficient in its construction and use, can be easily and cheaply manufactured and assembled for use, and will not be liable to become destroyed or injured when in use.

To these ends the invention consists, generally stated, in the novel arrangement, construction and combination of parts, as

hereinafter more specifically set forth and described and particularly pointed out in 55 the claims.

To enable others skilled in the art to which this invention appertains to construct, use and apply the improved tile for pavements, etc., the accompanying drawing will 60 be referred to in which—

Figure 1 is a top plan view of a sidewalk showing the improved tile applied thereto. Fig. 2 is a section of the same on the line 2—2 of Fig. 1. Fig. 3 is a perspective view 65 of one of the tiles removed. Fig. 4 is a bottom view of the same.

Like symbols of reference herein indicate like parts in each of the figures of the drawing.

As illustrated, the sidewalk or other like construction *a* is built up in any approved and suitable manner to form the spaces *b* therein for the glass tile 1, as hereinafter described, and when such tiles are in place, 75 the top of the sidewalk is finished by pouring and spreading of cement *c* which fills all voids and crevices in the parts. The cement is then troweled down to a smooth finished surface and even with the top 80 surface of said tiles, and when dry and set forms the finished structure.

The glass tile 1 is formed of two or more pieces 2 of glass, which are made or cut to the required size and shape in any suitable 85 manner, and if desired, connected together, and as shown the body 1' of the tile is formed of four pieces of the same size and shape, while an inner or bottom piece 3 is formed of a smaller size, in order to form 90 a shoulder or rabbet portion 4 by the side edges of the same and the bottom of the next succeeding body piece for supporting the tile in the spaces *b*.

The pieces 2 forming the body 1 and bottom 95 3 of the improved light or tile 1 may be secured together in any suitable manner, such as by a suitable cement, and when used form a solid and compact tile for instant use. When the tile 1 is placed within the 100 sidewalk *a* and used, the upper, lower and intermediate pieces or members forming such tile will be thus free to expand and contract in accordance with the varying influences by which it is affected, whereas, a tile 105 made of one piece only, is subjected to all

the varying conditions at once, the result of which is unequal expansion and contraction which seeks relief in sudden fracture, and causes the condition of broken tiles, 5 leaking sidewalks and unsightly surfaces at present complained of by occupants of vaults and basements constructed of one piece glass tiles. It will thus be seen that a glass tile formed of separate pieces reduces 10 expansion and contraction to a minimum, while practical experience with a tile so described has proven its standing without injury under the above conditions, and being formed of a plurality of pieces of glass of 15 nearly uniform thickness throughout the tile is practically without strain.

It will be understood that the improved tile can be placed in skylights, vertical and otherwise and that various modifications and 20 changes in the material, design, shape and application of the same may be resorted to without departing from the spirit of the in-

vention or sacrificing any of its advantages.

What is claimed as the invention and desired to be secured by Letters Patent is:

1. An article of the class described including a plurality of superposed horizontal laminations of transparent material, said laminations being capable of being supported as an integer.

2. An article of the class described including a plurality of superposed horizontal laminations of transparent material, said laminations being capable of being supported as an integer, and a film of transparent 30 adhesive material between the laminations for uniting the laminations.

In testimony whereof, I the said HENRY C. SEIPP have hereunto set my hand.

HENRY C. SEIPP.
